FURNITURE LIFT

Sherman R. Gillpatrick, Riverview Route, Riverton, Wyo.
Filed July 19, 1961, Ser. No. 125,252
4 Claims. (Cl. 294—16)

This invention relates to what might be termed an attachment for carrying articles of furniture. Large pieces of furniture such as over-stuffed davenport, sofas, and the like are exceedingly difficult to pick up and carry. On such pieces, it is exceedingly difficult to find satisfactory hand holds for carrying the pieces and for turning them to the various angles necessary to enable them to pass through doorways, stairways and the like. The limited space between these large pieces and the doorways makes it impossible for the handler to position his hands on the sides of the piece without damaging the hands.

The principal object of this invention is to provide simple, highly efficient, and easily applied carrying lifts or attachments which can be quickly attached to and detached from a piece of furniture to provide convenient outwardly projecting handles at both extremities of the piece so that it may be easily carried and turned for passage through doorways without damage to the hands, the doorway, or the furniture.

Another object of the invention is to provide a furniture carrying attachment which can be quickly applied to any desired piece of furniture regardless of the size or shape of the piece and to so design the attachment that it will automatically engage the piece without damage to the latter to provide three hand grips at each extremity of the piece of the furniture so arranged, relative to each other, that the furniture may be carried in an upright position, an inclined position, a side position or a completely inverted position.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

FIG. 1 is a perspective view of the improved furniture carrying attachment looking toward the inner side thereof;

FIG. 2 is an enlarged fragmentary, broken away, longitudinal section taken on the line 2—2, FIG. 1;

FIG. 3 is a reduced scale side elevational view showing the improved furniture carrying attachment as it would appear applied to one end of a piece of furniture such as a davenport 10 having conventional legs 11. A similar attachment is applied to the opposite end as shown in broken line; and

FIG. 4 is a fragmentary end view of the attachment illustrating how a castor wheel may be applied thereto.

Each of the furniture carrying attachments of this invention employs a telescoping base member consisting of a first base tube 12 and a second base tube 13. The base tubes are formed from and are telescopically fitted together by means of a connecting bar 14, of square cross section, permanently fitted into and projecting from one extremity of the first base tube 12 and slidably entering the adjacent extremity of the second base tube 13 into contact with a compression spring 15. The bar 14 is preferably provided with an enlargement or terminal collar 16 secured in place in any desired manner such as through the medium of an attachment rivet 17. A square

2

cap 18 is fitted over the extremity of the second base tube 13 and secured in place thereon in any desired manner such as by means of a set screw 19. The cap is provided with a square guide opening through which the bar 14 slides and the collar 16 and the cap 18 act to prevent the bar 14 from being completely withdrawn from the tube 13. The bar 14 can be locked in any desired position in the second base tube 13 by means of a third hand set screw 20.

10 A preferably square cross tube 21 is welded or otherwise fixed mounted across the other extremity of the first base tube in T-shaped relation thereto, and a similar cross tube 22 is similarly welded across the other extremity of the second base tube 13. The outer extremities of the cross tubes 21 and 22 are respectively provided with convenient, resilient hand grips 23 and 24. The hand grips may be of the conventional rubber, bicycle-handle-type grips forced over the outer extremities of the cross tubes and are preferably cemented in place thereon.

15 Square extension rods 25 and 26 are slidably fitted into and project from the inner extremities of the cross tubes 21 and 22, respectively. The extension rods can be locked at any desired projected position in the cross tubes 21 and 22 by means of suitable hand set screws 27 and 28, respectively. A stud 29 is mounted in and projects outwardly from the extremity of the extension rod 25 and a similar stud 30 projects oppositely outward from the extremity of the plunger rod 26. The studs 29 and 30 are surrounded by lengths of rubber tubing or other protective sleeves 29 and 30, respectively.

20 A riser tube 33 is welded to and arises vertically from the first extremity of the tube 12 to receive a telescopically-fitted clamping bar 34. A second compression spring 35 constantly urges the clamping bar 34 upwardly and the latter can be locked in any desired vertical position by means of a fourth hand set screw 36. To prevent complete withdrawal of the clamping bar, it is preferably provided with a stop collar 37 which prevents complete withdrawal of the bar through a tube cap 38 fixedly mounted on the upper extremity of the riser tube 33. The upper extremity of the clamping bar 34 is turned at right angles to the axis of the bar to form a horizontal clamping arm 39 which is also surrounded by a resilient protective sleeve 38.

25 A vertical handle tube 41 is welded or otherwise fixedly mounted at the outer extremity of the second base tube 13. The upper extremity of the handle tube 41 is turned at right angles to the axis of the tube to provide a handle arm 42 over which a third resilient hand grip 43 of the bicycle-handle-type is fitted.

30 In use, the fourth set screw 36 is loosened and the clamping arm is rotated and set in the plane of the base tubes as indicated at 39 in FIG. 3. The third set screw 20 is loosened and the hand grips 23 and 24 are gripped in the two hands. The latter hand grips are now forced toward each other, against the bias of the spring 15, so that the two studs 29 and 30 can be passed beneath the davenport 10 between the legs 11 at one end of the piece. The hand grips are now released allowing the spring 15 to force the cross tubes 21 and 22 outwardly against the legs 11 after which the set screw 20 is tightened to maintain the base tubes in the expanded position with the studs 29 and 30 engaged behind the legs 11. The set screw 36 is now loosened to allow the spring 35 to force the clamping arm 39 upwardly, the clamping arm is swung inwardly over the arm of the davenport 10 and is then forced downwardly into snug engagement with the arm where it is locked by means of the fourth set screw 36 as shown in FIG. 3. A similar furniture carry-

ing attachment is applied to the other extremity of the davenport 10, as indicated in broken line in FIG. 3.

It will now be noted that each extremity of the piece of furniture is provided with three projecting hand grips. Thus, if a man at each end of the davenport gripped the hand grips 23 and 24 at that end they can conveniently carry the piece in the upright position of FIG. 3. If they change their hands to grip the hand grips 43 and 24, they can readily carry the furniture in a sideward position, or if they change their hands to grip either one of the hand grips 23 or 24 and the hand grip 43, they can carry the piece in a diagonal position for convenient passage through a doorway.

To remove the attachment it is only necessary to loosen the third set screw 36 allowing the spring 35 to lift the clamping arm 39 from the arm of the piece of furniture. The clamping arm is then rotated to a sideward position as indicated in broken line at 39' in FIG. 3 and the set screw 20 is loosened so that by pressing the two hand grips 23 and 24 toward each other the studs 29 and 30 will be released from the legs 11 allowing the attachment to be withdrawn.

For one man use a wheel such as a castor wheel 44 may be attached to the cross tubes 21 and 22 of one or both of the attachments in any desired manner such as by means of U-bolts 45 as shown in FIG. 4. The wheel is positioned outwardly from the base tubes 12 and 13 adjacent to or below the hand grips 23 and 24.

With the wheels 44 in place and with the attachments in place on a piece of furniture such as a davenport, a single man can lift one extremity of the davenport by means of the hand grips 23 and 24 of one attachment so that the wheels 44 of the other attachment will engage the floor. He can then push or pull the piece of furniture without assistance at the other attachment.

While a specific form of the improvement has been described and illustrated herein, it is to be understood that the same may be varied within the scope of the appended claims, without departing from the spirit of the invention.

Having thus described the invention what is claimed and desired to be secured by Letters Patent is:

1. An attachment for carrying a piece of furniture

provided with legs comprising: a horizontal, longitudinally-extendable base bar; a cross bar fixed on each extremity of said base bar in T-shaped relation therewith so that when said base bar is extended said cross bar will come in contact at their inner extremities with the inside faces of two of said legs; a stud projecting outwardly from each inner extremity of said cross bars in axial alignment with each other so as to hook behind said legs; a hand grip on the outer extremity of each cross bar; a vertical riser tube mounted on said base bar and extending upwardly intermediate said cross bars; a clamping bar mounted in and extending upwardly from said riser tube; a horizontal clamping arm formed on and projecting horizontally inward from said clamping bar over said piece of furniture; and means on said riser tube for locking said clamping arm in engagement with said piece to maintain said base bar in place thereon.

2. An attachment for carrying a piece of furniture as described in claim 1 having: a vertical handle tube formed on and projecting upwardly from one extremity of said base bar and a handle arm projecting horizontally outward from the upper extremity of said handle tube substantially parallel with but in a direction opposite to said clamping arm to provide in combination with said hand grips three outwardly projecting hand engaging means in triangular relation to each other.

3. An attachment for carrying a piece of furniture as described in claim 2 having resilient means tending to constantly increase the length of said base bar.

4. An attachment for carrying a piece of furniture as described in claim 3 having resilient means tending to constantly urge said clamping arm upwardly away from said piece.
